James Norton & John Martino, of Philadelphia, Pa.

Assignors to

D. Stuart and R. Peterson, of same place.
Letters Patent No. 1315. Dated Sept. 3, 1860.

The schedule referred to in these Letters Patent and making part of the same.

To all whom it may concern:

Be it known that we, James Norton and John Martino, of the City and County of Philadelphia, and State of Pennsylvania, have invented or produced a new and original design for the plates of a cylinder stove, and we do hereby declare, the accompanying drawing with the following explanation of the same forms a full, clear, and exact description of the said design which relates to that class of Stoves in which cast iron base and cap, and a cylindrical body of sheet iron are used, the design relating to plates of the cap and base.

Fig. 1. represents the base of the stove in perspective.

Fig. 2, the same viewed from a different point.

Fig. 3, a perspective view of the underside of the cap.

Fig. 4, the same of the outside of the cap.

Fig. 5, a front view of the door and door frame.

Dec. 13 15

Fig. 6 a view of the urn. and

Fig. 7 a detached view of the leg of the Stove.

A. the lower plate of the base, is edged with mouldings formed of twisted beads interposed in front with tassels in bas relief--

The side plate B, has representations of a cord arranged in festoons with tassels, as seen in Fig. 1. the end plate C, having devices of a similar character--

The front plate D, Fig. 2, has also the cord and tassel ornaments, and has a door E, with a twisted bead, and knotted cord, interposed with scrolls, the top plate F, having the ornaments represented in Figs. 1 & 2.

The cap as seen in Fig. 4, has, on the top, ornaments of a character similar to that of the ornaments which form the plates of the base, the under side of the cap having the waved ribs shown in Fig. 3.

The ornaments on the door, and door frame, Fig. 5, are also similar in character to those of the other plates.

We claim the combination of ornamental figures and forms represented in and by the accompanying drawings, forming together an ornamental design for the plates of a cylinder stove--

In testimony whereof, we have signed our names to this Specification in the presence of two subscribing witnesses.
